UNITED STATES PATENT OFFICE.

JOHN NAPOLEON VALLEY, OF NORTH EAST, PENNSYLVANIA.

IMPROVEMENT IN FOLDING WASH-BENCHES.

Specification forming part of Letters Patent No. 123,955, dated February 20, 1872.

To all whom it may concern:

Be it known that I, JOHN NAPOLEON VALLEY, of North East, in the county of Erie and in the State of Pennsylvania, have invented certain new and useful Improvements in Folding Wash-Benches; and do hereby declare that the following is a full, clear, and exact description thereof, reference being had to the accompanying drawing and to the letters of reference marked thereon making a part of this specification.

The nature of my invention consists in the construction and arrangement of a "wash-bench," as will be hereinafter more fully set forth.

In order to enable others skilled in the art to which my invention appertains to make and use the same, I will now proceed to describe its construction and operation, referring to the annexed drawing, in which—

Figure 1 is a perspective view of my wash-bench in position for use; and Fig. 2 is a longitudinal section of the same when folded.

A A represent two parallel side rails, connected by means of cross-bars B B, which are tenoned into each side rail. Near each end of each side rail A is hinged a post, C, which form the legs of the bench, the posts or legs C C at each end of the bench being connected by cross-bars B', forming, as it were, a frame hinged at each end of the bench, so that it can be folded up when not in use. A standard, D, is fastened on top of each rail A in the center by a hinge, so that it may be raised or let down at pleasure, said standards being connected near their lower ends by a cross-bar, B², and at their upper ends by a bar or board, E. A continuous spring-brace, G, is pivoted on the out-

side of each side rail A, and runs from the leg C to the standard D, the two braces running in opposite directions, and their ends springing over pins a a attached to said legs and standards. The cross-bar or board E, which connects the upper ends of the standards D D, is designed to attach the wringer to; and at the lower edge of said cross-bar or board is attached a trough, H, to conduct the water, when using the wringer, back into the tub. The hinges b b, which connect the legs C C and standards D D to the side rails A A, are made in the shape of an elbow, as shown in Fig. 2.

The advantages of this wash-bench are, mainly, the cheapness of construction and its convenience in use, as it is so constructed that any wringer may be attached to the cross-bar E of the standards to wring the clothes, so that they may be run from one tub to another in the process of wringing, or from a tub to a basket; also, its convenience to be folded up and put away when not in use.

Having thus fully described my invention, what I claim as new, and desire to secure by Letters Patent, is—

The within-described wash-bench, consisting of the side rails A A, legs C C, standards D D, cross-bars B, B¹, B², and E, spring-braces G G, and trough H, all constructed and arranged substantially as and for the purposes herein set forth.

In testimony that I claim the foregoing I have hereunto set my hand this 27th day of December, 1871.

JOHN NAPOLEON VALLEY.
